ELECTROMAGNETIC RELAY

Cecil A. Lambert and George L. Webb, Logansport, Ind.,
assignors to Essex Wire Corporation

Application May 9, 1957, Serial No. 658,098

4 Claims. (Cl. 200—87)

This invention relates to electromagnetic relays and has more particular reference, but without restriction thereto, to relays of the type that are especially suited for use in automotive directional signal systems of the character disclosed in U.S. Patent No. 2,659,838, granted on November 17, 1953, to G. A. Du Rocher.

In general, turn signal systems of this type employ a pair of multiple contact relays electrically interconnected with each other and connected in a number of electrical circuits such as the turn signalling selecting switch, the automatic cancelling switch, the brake switch, the flasher, and the lamp circuits of an automobile. Prior art relays used for this application have generally been of complicated construction and require a considerable amount of space. Also, the use of prior art relays has required the use of a large number of electrical conductors for interconnecting the relays.

Accordingly, an object of the present invention is to provide an improved relay control device of rugged and compact construction which is efficient in operation and is more economical to manufacture than prior art devices.

One of the specific objects of the present invention is to provide an improved arrangement for supporting the armature and biasing it to its normal setting, which arrangement permits free movement of the armature.

Another object of the invention is to provide a fulcrum or rocking seat for the armature to which the armature is secured by an arrangement which permits ready adjustment of the relay characteristics.

Still another object of the invention is to provide an improved actuator unit by which the movement of the armature is transmitted to several contact springs.

A further object is to provide an improved arrangement for supporting the entire relay wherein the relay is disposed in a recessed portion of a base which base also supports the relay switch contacts and the terminals of an electric circuit.

Other objects, advantages, and novel aspects of the invention will appear in the following description and the accompanying drawings wherein a preferred form of the invention is shown.

In the drawings:

Figure 1 is a top plan view of a control device embodying my invention, the cover being removed.

Figure 2 is a transverse sectional view taken approximately on line 2—2 of Figure 1.

Figure 3 is an elevational view looking at the right side of the control device as viewed in Figure 1.

Figure 4 is an elevational view of the switch cover.

Figure 5 is a perspective view of the heelpiece and the elements of the armature assembly shown disassembled but in their proper order of assembly.

Figure 6 is a perspective view of the control device base and three contact supporting elements.

Figure 7 is a fragmentary sectional view taken along the lines 7—7 in Figure 6.

Figure 8 is a plan view of an actuator element.

2

Figure 9 is a side elevational view of the actuator element shown in Figure 8.

Figure 10 is an elevational view of two actuator elements joined together to form an actuator unit.

Figure 11 is a plan view of the control device looking at the opposite side of the control device as viewed in Figure 1.

Figure 12 is a schematic diagram illustrating conventionally the control device and its coils and contacts as well as the wiring diagram related thereto.

The control device illustrated in the drawings and hereinafter described is specifically designed for controlling automotive turn signal and brake signal lamps as in the above mentioned Du Rocher patent. This invention is not limited to such turn signal systems nor is it limited to the precise number of contacts or relay units specifically disclosed here. As the description proceeds, it will be apparent that a greater or lesser number of relay units and switch contacts to be operated thereby may be employed while retaining important features of the invention.

The control device generally comprises a rectangular base 20 made of insulating material, two electromagnetic relay units 21 and 22, the parts of which are mounted on the base 20, and a cover 23 which with the base 20 encloses the relay units. The cover 23 is provided with tongues 24 to be bent under the edges on the base 20 to hold the cover in place. Attached to the cover 23 is a bracket 25 by which the control device may be attached to a wall or panel (not shown).

The base 20 may be a single molded unit of insulating material having integral therewith all the necessary projections, apertures, etc., as hereinafter described. As more clearly shown in Figure 6, base 20 has a rectangularly shaped open side 26 exposing a recessed central portion 27 with a bottom wall 28. The major portions of relay units 21 and 22 are disposed within the recessed portion 27 and secured to wall 28.

Integral projections 29, 30, and 31 of base 20 are provided to support the ends of the contact springs 32, 33, 34, and 35 which are made of relatively thin flexible sheet metal stock. Rivets 36 serve to secure the contact springs 32, 33, 34, and 35 and their respective terminals 37, 38, 39, and 40 to the base 20 and to provide electrical connection between the contact springs and their respective terminals. A pair of contacts 32a is carried on the free end of the contact spring 32 and a second pair of contacts 35a is carried on the free end of the contact spring 35. Contact springs 32, 33, 34, and 35 have openings 41 through which extend the bosses 42. The purpose of these bosses is to insure that the contact springs are properly aligned. As can be best seen in Figures 6 and 7 recesses 43 around the bosses 42 enable the contact springs to lay flat against their respective projections 29, 30, and 31.

The reduced diameter portions of contacts 44 and 45 respectively, pass through the projections 46 and 47 of the base 20 and by means of their upset ends 48 serve to attach terminals 49 and 50 respectively to the base 20. Terminal 51 and the connecting strip 52 are similarly secured to the base 20 by contact rivets 53 and 54 passing through projections 47 and 46. Between the projections 46 and 47, two supporting legs 55 and 56 formed of metal stock are secured to the base 20 by the contact rivets 57 and 58 respectively and are utilized as supporting elements of the two stationary contacts 59 and 60. A third supporting leg 61 having arms 62 and 63 respectively supporting stationary contacts 64 and 65 is similarly attached to terminal 66. No terminal connections to rivet contacts 54, 57, and 58 are required and their ends are upset against washers 54a, 57a, and 58a respectively.

The electromagnetic operating mechanisms for displacing the contact springs is mounted in the recessed cen-

tral portion 27 of the base 20. The electromagnetic operating mechanism of relay unit 21 includes a frame 67 of magnetic material, a magnetic core 68 secured to the frame 67 and carrying a coil 69, an armature 70 pivotably mounted on the frame 67 and co-operating with the pole face 71 at the end of core 68, and actuator elements 72 secured by rivet 73 to the armature for switching engagement with the contact springs.

The frame 67 has a substantially Z-shape and includes a body 74 terminating in two oppositely directed arms 75 and 76. The core 68 has a reduced diameter portion 77 which passes through the opening 78 in the frame arm 75 and the opening 79 in the base bottom wall 23 to secure terminal 80, core 68, and frame 67 to the base 20. The frame arm 75 has two pins 81 integral therewith formed by punching which are received in the recesses 82 in the bottom wall 23 to align the frame 67 in respect to the base 20. The coil 69 is wound on the core 68 between the two end insulators 83 and 84 which are suitably held on the core 68. Coil lead 85 is soldered to terminal 86 which with terminal 87 is secured to the base 20 by rivet 88. The other coil lead not shown is electrically connected to the core 68 as by soldering. In relay unit 22, coil 89 is electrically connected to terminals 87 and 90 in a similar manner.

At its junction with the body 74, the frame arm 76 has a convexly curved surface 91 to provide a fulcrum or seat upon which the armature 70 is mounted for rocking movement. Projecting from the frame body 74 at either side of the curved surface 91 are two tabs 92 to accommodate the armature 70 at corresponding notches 93. There is sufficient clearance between the tabs 92 and the notches 93 to permit the armature 70 to freely rock on the curved surface 91 toward and away from the pole face 71 of the core 68. This armature mounting arrangement affords a low reluctance path yet is simple and rugged with minimum frictional losses.

To move the contact springs back and forth between the opposed contacts adjacent the contact ends of the contact springs 32, 33, 34, and 35, the armature 70 is provided with a pair of interlocked actuating elements 72 made of insulating material. The actuating elements 72 are secured to the armature by rivet 73 which also serves to secure the contact spring 94 or 95 on the opposite side of the armature 70. The actuator element 72 is maintained aligned with respect to the armature 70 by recesses 72a in the actuator element 72 into which extend the pins 70a formed integral with the armature by punching. Each of the actuating elements are identical in size and shape and include on one side a small detent or lug 96 at each end for engagement with the contact springs and a pair of centrally-located raised shoulders 97. The shoulders 97 have substantially the same shape and size as the openings between the shoulders 97 so that two actuating elements 72 can be assembled together as in Figure 10 to provide an actuator device having opposed pairs of lugs 96 for engaging the contact springs. Thus an improved actuator device of a shape difficult to form in a single integral unit is simply and economically formed from two identical parts made from the same set of molding dies.

The armature 70 is clamped to the frame 67 and is normally biased away from the core pole face 72 by an arrangement comprising a coil spring 98 positioned between the head 99 of screw 100 and a recessed portion 101 of the armature 70. The screw 100 passes through an opening 102 in the armature and is received by the threaded hole 103 in the arm 76 of the frame 67. Recessed portions 104 in the base 20 prevent binding of the end of the screw 100 against the base 20. The spring 98 is thus utilized for the dual purpose of clamping the armature 70 against the frame curved surface 90 and of biasing the armature 70 in a direction to move the actuator elements 72 away from the core pole face 71. In

addition, spring 98 insures good electrical connection between the frame 67 and the armature 70 as part of the current path to coil 69 or 89 including core 68 and the contact spring 94 or 95. The biasing force and hence the contact pressure of the normally closed contacts and the relay pull in voltage may be selectively varied or adjusted by varying the elevation of the screw head 99 with respect to the frame arm 76.

Referring to Figure 12, the electrical circuit of the control device described above in connection with Figures 1-11 is shown with the several parts and terminals of the control device indicated by like reference numerals. Figure 12, in addition, shows the connection of the control device in an automotive directional signal system according to the above mentioned Du Rocher Patent No. 2,659,838. In this system, the control device together with a manually operated signalling and cancelling switch 105, an automatic cancelling switch 106, and a flasher switch 107 control a pair of signal lamps 108 and 109 for signalling a right turn of a vehicle at the front and rear thereof respectively and a second pair of signal lamps 110 and 111 at the front and rear respectively of the vehicle for signalling a left turn. The right and left rear lamps 109 and 111 are also energized as stop signalling lamps when not used to signal a turn by the brake pedal operated switch 112. The operation of the directional signal system shown is in accordance with the showing and teaching of the above mentioned Du Rocher patent.

From the foregoing explanation, it will be understood that the arrangement of the various components of each relay unit and also the disposition of the contacts and contact springs on one side of the base in spaced relationship around the electromagnetic operating mechanisms which are disposed in a recessed portion of the base result in an extremely compact arrangement. Further by directly attaching the fixed contacts and the contact springs to terminals located on the opposite side of the base, further compactness of arrangement is afforded.

Another advantage of this construction is that a cover of minimum size may be used to enclose all exposed relay parts.

While the invention has been illustrated and described in its preferred embodiment and has included certain details, it should be understood that the invention is not to be limited to the precise details herein illustrated and described since the same may be carried out in other ways, falling within the scope of the invention as claimed.

What is claimed is:

1. In an electromagnetic relay, in combination, a base member, a magnetic field structure attached to said base member, an electromagnetic operating winding carried by said field structure, a movable armature controlled by said electromagnetic operating winding, a pair of contact springs supported adjacent said armature, and a pair of interlocked actuating elements of insulating material secured to said armature for transmitting movement of said armature to said springs, each of said actuating elements having on one side a pair of centrally located shoulders and a pair of lugs for co-operation with said contact springs, said shoulders having substantially the same shape and size as the openings between said shoulders to permit interengagement of said shoulders with each other, the lugs of one of the actuating elements being directed to the lugs of the other actuating element on opposite sides of said contact springs.
2. A movement transferring device for electromagnetic relay springs comprising two actuating elements of insulation material having identical size and shape, each of said actuating elements having a body portion from one side of which project a pair of centrally located shoulders and a pair of lugs for co-operation with said relay springs, said shoulders having substantially the same shape and size as the openings between said shoulders, the lugs of one of the actuating elements being di-

rected to the lugs of the other actuating element in a spaced relationship when the shoulders of one actuating element are seated in the openings between the shoulders of the other actuating element.

3. An electromagnetic relay comprising: a base member of insulating material having a recessed portion; a magnetic field structure mounted in said recessed portion; a winding carried by said field structure; a magnetic armature movable between magnetically attracted and unattracted positions; two contact springs disposed in substantially parallel relation adjacent opposite sides of the armature; said base member having two longitudinally extending bosses integrally projecting from said base member; said base member having a recess surrounding and immediately adjacent each of said bosses at the junction thereof to said base member; each of said contact springs including a strip of resilient material secured at one end to said base member adjacent one of said bosses; each of said strips of resilient material including a longitudinally extending slot therein for receiving one of said bosses; stationary contacts supported by said base member; movable contacts carried by said contact springs for cooperative engagement with said stationary contacts; and means transmitting movement of said armature to said contact springs.

4. The electromagnetic relay of claim 3 wherein said means transmitting movement of the armature to said

contact springs comprise: two interlocked actuating elements of insulating material secured to the armature; each of said actuating elements having a body portion from one side of which project a pair of centrally located shoulders and a pair of lugs for cooperation with said contact springs; said shoulders having substantially the same shape and size as the openings between said shoulders; the lugs of one of the actuating elements being directed to the lugs of the other actuating element in a spaced relationship when the shoulders of one actuating element are seated in the openings between the shoulders of the other actuating element; each of said contact springs passing between two of said spaced lugs.
